UNITED STATES PATENT OFFICE.

RICHARD THIERFELDER, OF MILWAUKEE, WISCONSIN, ASSIGNOR TO PHOENIX KNITTING WORKS, OF MILWAUKEE, WISCONSIN, A CORPORATION OF WISCONSIN.

WEARING-APPAREL.

1,206,171.

Specification of Letters Patent.

Patented Nov. 28, 1916.

Application filed October 30, 1915. Serial No. 58,736.

To all whom it may concern:

Be it known that I, RICHARD THIERFELDER, a citizen of the United States, residing at Milwaukee, in the county of Milwaukee and State of Wisconsin, have invented a certain new and useful Improvement in Wearing-Apparel, (Case 1,) of which the following is a full, clear, concise, and exact description, reference being had to the accompanying drawings, forming a part of this specification.

My invention relates to wearing apparel and is concerned with the support of such articles upon one's person.

More particularly my invention has to do with the adequacy and comfort of the support and with the efficient distribution of the strain upon the garment and it is the purpose of my invention to provide an improvement whereby both of these objects are at once accomplished.

Although it will appear to those skilled in the art that my invention is adapted to any adaptable type of woven garment, I have in mind especially its applicability to stockings wherein excessive strain or improperly distributed strain results in the rupture of the weave to cause what are commonly known as "runs", to say nothing of the discomfiture to which the wearer is subjected and the absence of uniform smoothness. I shall therefore illustrate and describe in detail a stocking employing my invention, as an example thereof, to instruct those skilled in the art, but shall claim my invention in any adaptable use where it may be of advantage.

As applied to a stocking, I provide a flap which, in formation, is in the nature of a circular plait, a seam simultaneously forming the complete circular plait and forming a barrier to the concentrated transmission of the strain incident to an applied garter from the upper portion of the stocking to the lower portion thereof.

In order to describe my invention in detail I shall refer to the accompanying drawing, in which,

Figure 1 illustrates a stocking employing the features of my invention, Fig. 2 is a sectional view, in part, taken on the plane of the line 2, 2 of Fig. 1, and looking in the direction indicated by the arrows, and Figs.

3 and 4 are diagrammatic views which will be referred to.

The body of the stocking is illustrated at 5 and the foot thereof at 6. The top of the stocking is made in double thickness, in the nature of a hem, as illustrated at 7, 7, the two thicknesses being joined at 8. Below 60 the line 8, which, of course, extends entirely around the stocking, a plait 9 is formed, in the manner illustrated diagrammatically in Fig. 3, this plait being determined by a weft seam at 10, this seam being 65 preferably formed by stitches made during the manufacture of the body of the stocking. This seam extends entirely around the stocking parallel to the line 8, which has been referred to. It is a matter of common practice to provide the upper part of the stocking with a different weave, and probably a different material, from that of the lower part of the stocking, and my invention may be involved whether or not 75 that popular practice is followed out.

As illustrated, the plait 9, which forms a flap, is provided near the top of the stocking, but the width of plait or flap is less than the distance between the seam 10 and 80 the upper end of the stocking. It will be seen that the garter may be applied either to the upper end of the stocking, at the double thickness 7, 7, or it may be applied to the plait or flap 9, depending upon which 85 gives a sufficient support but not an excessive strain. The provision of the seam 10 prevents the concentrated transmission of the pull of the garter from the point above the seam, whether the garter is applied to the parts 7, 7 or the part 9, and effectively distributes the strain over a greater area so that the strain may be properly met by the weave below. This prevents premature rupture of the weave 95 and avoids "runs", as hereinbefore pointed out.

It is obvious that, due to the overlapping of the plait and hem, when a garter is applied to the plait the leg of the wearer will 100 be protected therefrom by the double thickness of the hem, the friction then taking place between the layers of the hem.

If desired, as shown in Fig. 4, the upper end of the double thickness 7, 7 may be 105 folded outwardly and downwardly back

upon itself and over the flap or plait 9, thus securing a texture of quadruple thickness to which the garter may be applied, if desired.

I claim:

- 5 A stocking having a hem at the top thereof and an integral circular plait formed by a seam extending entirely around said stocking and located below said hem, said plait overlapping said hem upon the outside and

terminating below the top of said hem, 10 whereby the leg of the wearer is protected from contact with a garter attachment secured to said plait by the double thickness of said hem.

In witness whereof, I hereunto subscribe 15 my name this 26th day of October, A. D. 1915.

RICHARD THIERFELDER.
